[57] CLAIM

The ornamental design for a trash container cart, as shown and described.

DESCRIPTION

FIG. 1 is a perspective view of a trash container cart, showing my new design;

FIG. 2 is a front elevational view thereof;

FIG. 3 is a left side elevational view thereof, the right side elevational view being a mirror image thereof;

FIG. 4 is a rear elevational view thereof;

FIG. 5 is a top plan view thereof;

FIG. 6 is a bottom plan view thereof;

FIG. 7 is a cross-sectional view taken along the line 7—7 of FIG. 5.
